SUPPLEMENTAL SIGNALING SYSTEM FOR
SPECIAL RAILWAY VEHICLESHoward A. Thompson, Edgewood, Pa., assignor to
Westinghouse Air Brake Company, a corpora-
tion of Pennsylvania

Application September 25, 1948, Serial No. 51,276

7 Claims. (Cl. 246—63)

1

My invention relates to railway signaling systems, and particularly to supplemental signaling systems for governing the movement of special railway vehicles which move independently of the usual block signal systems.

Special railway vehicles, such as small motor cars used by maintenance men, are usually equipped with insulated wheels or axles so that these cars will not shunt the track circuits of signaling systems which govern train movements. As a result, the conventional railway signaling systems do not protect the operator of a motor car or other special vehicle of that character.

An object of the present invention is to provide an improved supplementary signaling system for indicating to operators of special vehicles of the type designed that a train is approaching.

Another object is to provide an improved supplementary signaling system for the continuous control of moving vehicles of a special character which may be superimposed without interference upon a conventional cab signaling or train control system for the continuous inductive control of standard railway vehicles.

The supplemental signaling system of my invention is an improvement upon those described in the copending applications for Letters Patent of the United States, Serial No. 996, filed January 7, 1948, and Serial No. 5,138, filed January 29, 1948, by Wilbur V. Grosjean, both of which are entitled Supplemental Signaling Systems for Special Railway Vehicles. The improvements provided by my invention comprise the provision of means for selectively supplying motor car indicator control energy or cab signaling energy to each of the sections of a stretch of railway track in response to traffic conditions, and the provision of means for selectively changing the character of the motor car indicator control energy to thereby indicate the direction from which a train is approaching a section or sections of track in the stretch.

Another object of my invention is to provide a supplemental signaling system which gives to the operator of a special vehicle a positive indication of the direction of movement of an approaching train.

A further object is to provide an improved supplemental signaling system for the operation of special wayside indicators which govern the movement of special vehicles only.

A further object of my invention is to provide an improved supplemental signaling system including means for preventing a receding train from giving a false indication that a train is approaching.

2

My invention is disclosed herein as applied to two different types of conventional block signal systems. One type of system is an absolute permissive block system controlling the movement of trains over a single track stretch having spaced passing sidings. The other type of system disclosed is a block signal system adapted for use on each track of a multiple-track railway, which block signal system controls movements over the track in one direction only. Both of the systems disclosed employ conventional direct current track circuits and supply coded alternating current to the track rails for the control of train-carried cab signaling or train control equipment of the continuous inductive type, such as is shown, for example, in Letters Patent of the United States No. 1,986,679, issued January 1, 1935, to Lloyd V. Lewis for Railway Traffic Controlling Apparatus.

In both of the supplemental signaling systems described herein, the special vehicles are each provided with a receiving relay responsive to alternating current in the track rails which controls visual and audible indicators. The motor car carried apparatus is so arranged that a lamp is steadily lighted as long as the relay is energized by steady alternating current supplied to the track rails, thus indicating to the operator that no train is approaching from either direction. The lamp is extinguished and an audible signal is sounded when the supply of current is interrupted.

It follows that either the absence of alternating current or the presence of alternating current interrupted at a specified rate, such as 180 times per minute, as provided for the control of the cab signals on an approaching train constitutes a warning to the operator of a motor car that this should be removed from the track.

In the absolute permissive block signaling system disclosed herein, the indications received by the motor car operator additionally indicate the direction of approach of a train. When a train approaches from one direction, the supply of alternating current is cut off, while the approach of a train from the opposite direction interrupts the supply of alternating current intermittently at a predetermined low rate, such as 15 times per minute, which is readily distinguishable from the cab signaling frequencies mentioned. In either case the supply of motor car indication current is cut off by the shunting effect of the wheels and axles of the train when it enters the section occupied by the motor car.

In the single direction signaling system described herein, wayside motor car indicators are

provided for the control of the special railway vehicles, in addition to the indicators carried by the motor cars themselves. This supplemental signaling system utilizes line circuits extending between successive signal locations and forming part of the conventional block signaling system. In the supplemental system, a series approach relay is added at the advance or energy supply end of each of these line circuits, which controls the supply of energy from an adjacent local source to a second line circuit which extends to the next succeeding signal location in advance. This second line circuit is provided, in accordance with the invention, for the control of a neutral relay and a biased polar relay at such location. The neutral relay operates pole-changing contacts in the corresponding second line circuit extending one block further in advance, while the biased polar relay operates means for controlling an adjacent wayside indicator and for controlling the supply of motor car indicator current to the track rails of the section through which its circuit extends. The operation is such that when a train enters a given section, it deenergizes the signal and also the series approach relay in the signal circuit at the location of the next signal in advance which opens the second line circuit extending to the location of the second signal in advance, deenergizing both the polar and neutral relays at that location. De-energization of that neutral relay pole-changes the second line circuit of extending to the location of the third signal in advance, thereby de-energizing the polar relay at that location. Since each polar relay controls the motor car warning indication for its particular section, it will be seen that a train moving in the normal direction will indicate its approach to a motor car occupying either of the two block sections ahead of the one occupied by the approaching train.

Although the signal system is arranged for the control of train movements in one direction only, it is assumed that at times train movements in the opposite direction will be made. The motor car indicator system provides protection for such train movements by utilizing the signal control circuits to cut off the motor car indicator current from the rails of a section in the rear of a signal which indicates caution or stop, that is to say, from the rails of the two sections ahead of a train which is moving in the direction opposite to the normal direction. Directional stick relays at each signal location prevent cutting off the motor car indicator current in this manner from the rails of the sections in the rear of a train moving in the normal direction.

I shall describe two signaling systems embodying my invention, and shall then point out the novel features thereof in claims.

In the drawings, Figs. 1A, 1B, and 1C taken together constitute a diagrammatic view of a stretch of railway track equipped with a conventional absolute permissive block signaling system and also with a supplemental signaling system incorporating certain features of my invention. Fig. 2 is a diagrammatic view of one form of indication equipment which may be carried on a railway motor car or other special vehicle to be used in cooperation with the wayside apparatus of my invention. Figs. 3A and 3B taken together form a diagrammatic view of a stretch of railway track equipped with a conventional block signaling system for single direction running and also with a modified form of supplemental signaling system embodying my invention.

Similar reference characters refer to similar parts in each of the several views.

Figs. 1A, 1B, and 1C

5 When these three figures are placed side by side with Fig. 1B at the right of Fig. 1A and Fig. 1C at the right of Fig. 1B, they illustrate my invention as applied to a stretch of single track between two passing sidings PS. When Fig. 1C is placed at the left of Fig. 1A, and Fig. 1B at the right of Fig. 1A, these drawings illustrate my invention as applied to the main track stretch adjoining a passing siding and interposed between two single track stretches.

10 In most instances in the drawings, the relay contacts are located directly below the winding of the relay which operates them. In order to simplify the drawings, however, the relay contacts have in some cases been separated from their associated winding. In these instances the relay winding is designated by appropriate reference characters placed above the contact.

15 When the drawings are arranged with Fig. 1B at the right of Fig. 1A, and Fig. 1C at the right of Fig. 1B, it may be seen that the stretch of single track shown extends from switch 1 in Fig. 1A, to switch 11 in Fig. 1B, and is provided with signals 3, 5, 7, and 9 controlling westbound traffic and signals 4, 6, 8, and 10 controlling eastbound traffic. The rails 1a and 1b are provided with insulated rail joints by which the main track is divided into track sections 1T, 4T, 5T, 6T, 7T, 8T, and 9T. Each section is provided with the usual normally closed track circuit including a track relay TR at one end energized by a track battery TB connected across the rails at the other end.

20 Circuit elements associated with a particular track section are indicated by alphabetical reference characters designating the type of element prefixed by numerical reference characters corresponding to the number of the particular section. For example, 6TR indicates the track relay TR for section 6T.

25 Each track section is provided with two track transformers W and E. Transformer W has its secondary winding connected across the track rails at the west end of the track section and supplies cab signaling current to the track rails for the control of westbound trains. Transformer E is connected across the track rails at the east end of the track section and supplies cab signaling current to the rails for the control of eastbound trains. Each transformer secondary at 30 the battery end of a track section is connected in series with the track battery. Each transformer secondary at the relay end of a track section is connected in parallel with the track relay. A suitable current limiting impedance is connected in series with the transformer secondary winding in each instance.

35 When alternating current is supplied to the primary winding of a track transformer, a similar current is induced in the secondary winding and thereby supplied to the rails of the track section. The windings of the track relays present a high impedance to the alternating current, so that the alternating current flowing through the track relay windings is negligible. Hence, alternating electrical current may be supplied to a track section without affecting the operation of the direct current track circuit in that section.

40 The wayside signals 3, 4, 5, 6, 7, 8, 9, and 10 are of the well-known searchlight type and may be constructed as shown in Letters Patent of the

United States No. 1,864,224, granted to Wesley B. Wells on June 21, 1932. Each signal is illustrated in the drawing as comprising a wayside structure shown beside the track rails and a correspondingly numbered mechanism having a control winding identified by the suffix G and appearing in the circuit plans substantially below the wayside structure. When the winding is energized with direct current of normal polarity, the signal gives a proceed indication by displaying a green light and a contact G is picked up. When the winding is energized with direct current of reverse polarity, the signal gives a caution indication by the display of a yellow light, and a contact Y is picked up. When the winding is de-energized both the contacts Y and G are released, and the signal gives a stop indication by the display of a red light.

A local battery or other suitable source of direct current is provided at each signal location to energize the circuits other than the track circuits. These sources are not shown in the drawings, but their positive and negative terminals are designated B and C, respectively. A source of alternating current, not shown, is also provided at each signal location, the terminals of which are designated BX and CX.

The signals 4, 5, 6, 7, 8, and 9 are provided with repeater relays PC. Each of these relays is arranged to be energized when either the Y or G contact of its associated signal is picked up.

The signals 3 and 10 are provided with repeater relays 3PC and 10PC which repeat the position of the G contact only of the associated signal and are also provided with repeater relays 3YP and 10YP which repeat the position of their Y contacts.

At the battery end of track section 1T, a repeating relay 1TPR is provided controlled by the relay 1TR at the opposite end of section 1T.

The signals 5, 6, 7, 8, and 9 are provided with directional stick relays 5S, 6S, 7S, 8S, and 9S. Each of these relays is picked up each time that a train accepts a proceed or caution signal and remains picked up until its associated signal is again restored to its proceed or caution position after the passage of a train. The pickup and stick circuits for these relays are conventional and referring to stick relay 5S, it may be seen that its pickup circuit extends from positive battery terminal B over a back contact of relay 5TR, over a front contact of relay 5PC, and through the winding of relay 5S to negative battery terminal C. When signal 5 indicates proceed or caution, relay 5PC is energized and its front contact is closed. If a westbound train accepts this signal, it deenergizes relay 5TR upon its entry into section 5T. The front contacts of relay 5PC remain closed for a short time after the winding of signal 5 is deenergized by the opening of the front contacts of relay 5TR. The length of time the front contacts of relay 5PC remain closed under these conditions is determined by the drop-out time of the contacts Y and G of signal 5 and of relay 5PC. In any event, the pickup circuit for stick relay 5S is closed during this interval. As soon as the winding of relay 5S is energized, it closes its front contact, completing a stick circuit which may be traced from the positive terminal B through a back contact of relay 5PC, and the front contact of stick relay 5S, the winding of relay 5S to the negative battery terminal C. This stick circuit remains energized until relay 5PC is again energized and opens its back contact.

The signals 3 and 10 are also provided with directional stick relays 3S and 10S, the pickup and stick circuits for which are somewhat different from the circuits of the other stick relays just described. This difference is occasioned by the fact that the relays 3PC and 10PC repeat only the proceed positions of the signals 3 and 10, whereas the PC relays for the other signals repeat both the proceed and caution positions.

The pickup circuit for stick relay 10S may be traced from positive battery terminal B through a back contact of relay 1TR, thence through front contacts of relays 10PC and 10YP in parallel to the winding of relay 10S and thence to negative battery terminal C. This circuit is completed through the front contact of relay 10PC whenever a train accepts a signal 10 at proceed. When a train accepts signal 10 at caution, the pickup circuit is completed through the front contact of relay 10YP. As soon as relay 10S picks up, it completes a stick circuit which may be traced from the positive battery terminal B through a back contact of relay 10PC and the front contact of relay 10S to the winding of relay 10S and thence to the negative battery terminal C. This stick circuit remains energized until relay 10PC is again energized, which occurs when signal 10 is again moved to its proceed position.

At each signal location there are located one or more code transmitting relays for cab signal purposes which are indicated by the reference characters 180CT in the drawings. This reference character indicates that the code transmitting relay opens and closes its contacts 180 times per minute. There are also provided at the several signal locations other code transmitting relays for use in the supplemental signaling system for motor cars, which are identified by the reference character 15CT in the drawings, indicating that they open and close their contacts 15 times per minute. These frequencies are chosen by way of example only, and other suitable frequencies may be used, provided they are sufficiently far apart to be readily distinguishable by the code responsive apparatus.

The several signals are energized by circuits which are generally conventional in an absolute permissive block type of signaling system. The particular circuits described are shown by way of example only, and other equivalent circuits may be readily used in carrying out my invention. The circuits for the single track stretch are arranged so that all signals normally indicate proceed, and each signal governing traffic in one direction is set to stop whenever a train approaching from the opposite direction enters the stretch. Also, when a train accepts a signal governing its movement, the signal is put to stop and continues to indicate stop as long as the train occupies the first block section immediately in advance of the signal. When the train vacates the first block section in advance, the signal indicates caution, and when the train vacates the second block section in advance, the signal indicates proceed.

The circuits for the signals which govern eastbound traffic movements through the single track stretch shown in Figs. 1A, 1B and 1C will now be traced in detail. When the track sections 8T and 9T are unoccupied, the winding 8G for signal 8, Fig. 1B, is energized over a circuit including a front contact of the track relay 8TR, a back contact of the directional stick relay 8S, line wires 31 and 32, a front contact of the track relay 9TR, and extending to terminals B and C

over pole-changer contacts of relay 10PC. Relay 10PC is picked up to supply current of normal polarity to this circuit to cause signal 8 to indicate proceed only when signal 10 indicates proceed, and the polarity is reversed to cause signal 8 to indicate caution when signal 10 indicates caution or stop. Relay 8PC picks up when winding 8G is energized, and if sections 7T and 6T are unoccupied, energizes winding 6G over a circuit including a front contact of relay 6TR, a back contact of relay 5S, line wires 33 and 34, and extending to terminals B and C over the front contacts of relays 7TR and 8PC. Relay 8PC when picked up supplies current of normal polarity to this circuit to cause signal 6 to indicate proceed when signal 8 indicates proceed or caution. When relay 8PC is released due to the occupancy of section 8T or 9T by an eastbound train, relay 8S is picked up and connects terminal B over a back contact of relay 8PC to the circuit for winding 6G so that this winding is energized by current of reverse polarity to cause signal 6 to indicate caution.

When winding 6G is energized, relay 6PC picks up and if sections 5T and 4T are unoccupied, winding 4G is energized by current of normal polarity over a circuit including a front contact of relay 4TR, line wires 13 and 15, and extending to terminals B and C over the front contacts of relays 5TR and 6PC, so that signal 4 indicates proceed when signal 6 indicates proceed or caution. When relay 6PC is released due to the occupancy of section 6T or 7T by an eastbound train, relay 6S is picked up and connects terminal B to this circuit so that current of reverse polarity is supplied to winding 4G to cause signal 4 to indicate caution.

Considering now the siding area, and placing Fig. 1C at the left of Fig. 1A; it will be seen that when the track sections 1T and 4T are unoccupied, winding 10G is energized over a circuit including a front contact of relay 1TR, line wires 35 and 36, a front contact of relay 4TR, and extending to terminals B and C at the pole-changer contacts of relay 4PC, which relay is picked up to supply current of normal polarity to the circuit to cause signal 10 to indicate proceed when winding 4G is energized to cause signal 4 to indicate caution or proceed, and supplies current of reverse polarity to cause signal 10 to indicate caution, when signal 4 indicates stop.

The circuits for governing westbound traffic movements are similar, that is to say, the circuits for controlling signals 9, 7, 5 and 3 correspond respectively to those for signals 4, 6, 8 and 10 just traced, and therefore will not be traced in detail.

As previously mentioned, coded cab signal current is supplied to the rails of the several track sections through transformers W or E located at the ends of their respective track sections. In the particular arrangement disclosed herein, the cab signal current is alternating current interrupted at a frequency of 180 times per minute, the train carried apparatus of the Lewis patent referred to being responsive to coded current of this frequency in the rails ahead of the train to cause the display of a "proceed" indication in the cab of the leading vehicle of the train. This train governing current is supplied to the rails of a given track section only when the signal immediately in advance of the section indicates proceed, and in certain cases it is supplied to the rails of a section only when such section is occupied by a train.

The supplemental signaling system for the control of the motor car indication apparatus of Fig. 2 normally supplies steady alternating current to the rails of each section for indicating to the operator of a motor car at any point in the stretch that no train is approaching within a predetermined distance from either direction. The direction from which a train is approaching is indicated by cutting off the supply of alternating current from one or more sections in front of a westbound train, and by interrupting the supply of alternating current supplied to one or more sections in front of an eastbound train at a code rate of 15 times per minute.

15 Normally, steady alternating current is supplied to the rails of section 4T by transformer 4W which is energized over the circuit from terminal CX through its primary winding, front contact *a* of relay 4TR and front contacts of relays 4PC and 3PC to terminal BX. Steady alternating current is normally supplied to the rails of sections 5T and 6T by transformers 5E and 6W which are energized over circuits including the line wires 37 and 38, front contacts *a* of the track 20 relays 5TR and 6TR, respectively, and extending over front contacts of relays 6PC and 5PC in series to terminal BX. Section 5T is also normally supplied with 180 code current by transformer 5W but this is without effect upon the 25 motor car apparatus when steady current is supplied to the same section. The circuit for transformer 5W extends to terminal BX over front contact *b* of relay 4TR, a front contact of relay 3PC and a contact of a code transmitter 180CT.

30 Steady alternating current is normally supplied to the rails of sections 7T and 8T by transformers 7E and 8W, which are energized over circuits including the line wires 39 and 40, front contacts *a* of relays 7TR and 8TR, respectively, and extending over front contacts of relays 8PC and 7PC in series to terminal BX. Section 7T is also normally supplied with 180 code current by transformer 7W which is energized over line wire 41, front contact *b* of relay 6TR, and front contacts 35 of relay 5PC and of the adjacent code transmitter 180CT.

35 Steady alternating current is normally supplied to the rails of sections 9T and 1T by transformers 9E and 1W, which are energized over front 40 contacts *a* of relays 9TR and 1TR, respectively, a back contact of relay 10S, and front contacts of relays 10PC and 9PC. Section 9T is also supplied with 180 code current by transformer 9W, the circuit for which includes front contact *b* of relay 8TR, a front contact of relay 7PC and a contact of a code transmitter 180CT.

45 The effect of the passage of a train through the stretch of track shown in Figs. 1A, 1B and 1C will now be explained in detail.

50 It will be assumed first that an eastbound train is occupying section 1T. Windings 10G and 3G are deenergized, due to the release of relay 1TR by the train so that signals 10 and 3 indicate stop and relays 10PC and 3PC are released, causing signal 8 at the left and signal 5 at the right to indicate caution, while all of the other signals indicate proceed. The track repeater relay 1TPR is released, causing transformer 1E to supply coded cab signal current to the rails of section 1T in front of the train to correspond with the proceed indication displayed by signal 4. The primary circuit for transformer 1E is now closed from terminal CX through its winding to terminal BX 55 over back contacts of relays 1TPR, 3PC, 3YP, a

front contact of relay 4PC and a periodically operating contact of a code transmitter 180CT.

Alternating current interrupted at the rate of 15 times per minute for motor car warning purposes is now supplied to section 4T in front of the train by transformer 4W, the primary circuit of which now extends over front contact *a* of relay 4TR, a front contact of relay 4PC, a back contact of relay 3PC, and a contact of a code transmitter 15CT to terminal BX at a back contact of relay 3S.

Transformers 5E, 6W, 7E, 8W, etc. continue to supply steady alternating current to the rails of their respective sections in front of the train, as well as to the similar sections behind the train. If the train entered section 1T from section 9T, relay 1TR is holding relay 10S picked up, and a front contact of relay 10S bridges the open front contact of relay 19PC in the circuit for transformer 9E so that steady alternating current is supplied to the rails of section 9T, otherwise transformer 9E is deenergized and a 180 code is supplied to section 9T by transformer 9W.

Considering for the moment that the train in section 1T is westbound, it will be seen that the 180 code current supplied by transformer 9W is provided as a motor car warning in section 9T and that transformer 1W is supplying 180 code for cab signal control to the rails of section 1T in front of this train to correspond with the proceed indication of signal 9. Furthermore, if the westbound train entered section 1T from section 4T, relay 3S is picked up to cause transformer 4W to supply steady alternating current to the rails of section 4T in the rear of the westbound train in place of 15 code.

Returning now to a consideration of the eastbound train, when it enters section 4T, the release of relay 4TR deenergizes winding 4G to put signal 4 to stop, releasing relay 4PC and also deenergizing in cascade the windings G and relays PC for the opposing signals 5, 7 and 9 ahead of the train so that these signals indicate stop, the release of relay 9PC causing the indications of signals 3 and 5 to change from proceed to caution, and when the eastbound train vacates section 1T, signal 3 in the rear indicates proceed and signal 10 in the rear indicates caution. Transformer 4E is energized as soon as the train enters section 4T to supply coded cab signal current to the rails in front of the train over back contact *c* of relay 4TR, front contact *b* of relay 5TR, a front contact of relay 6PC and a contact of a code transmitter 180CT.

In front of the train, the release of relay 5PC connects wires 37 and 38 to terminal BX over a contact of a code transmitter 15CT so that transformers 5E and 6W supply current interrupted at the 15 code rate to sections 5T and 6T, and also opens the circuit over wire 41 for transformer 1W. The release of relay 1PC similarly energizes transformer 7E and 8W over wires 39 and 40, to supply 15 code to the rails of sections 7T and 8T, and opens the circuit for transformer 9W, while the release of relays 9PC and 3PC causes transformers 9E, 1W and 4W to supply 15 code to the rails of sections 9T, 1T and 4T.

It will be seen, therefore, that when the eastbound train enters section 4T, the limit of the motor car warning territory is extended from the end of this section to the end of the corresponding section 4T of the next block in advance.

The release of the track relays as the train advances through sections 4T to 9T causes alternating current interrupted at the 180 code rate

to be supplied to the rails of the successive sections at their right-hand ends as each section is occupied by the train, for cab signal control. Transformers 5E to 9E are each energized for this purpose over a contact of a code transmitter 180CT, as follows: Transformer 5E over wire 37, back contact *a* of relay 5TR and a front contact of relay 6PC; transformer 6E over back contact *c* of relay 6TR, wire 42, front contact *b* of relay 7TR and a front contact of relay 8PC; transformer 7E over wire 39, back contact *a* of relay 7TR and a front contact of relay 8PC; transformer 8E over back contact *c* of relay 8TR, front contact *b* of relay 9TR, and a contact of relay 10PC; and transformer 9E over back contact *a* of relay 9TR and a front contact of relay 10PC, for signal 10 in front of the train.

Signal 10 in the rear of the train stands at caution and its relay 10PC is released, and if relay 10S is energized, transformer 1W is connected over front contact *a* of relay 1TR to the circuit for transformer 9T so that section 1T as well as each more remote section in the rear of the train is supplied with steady alternating current.

When the eastbound train occupies section 6T, signal 6 is put to stop by the release of relay 6TR, energizing relay 6S and releasing relay 6PC. Relay 6S opens its back contact in the circuit for winding 5G to maintain signal 5 at stop and energizes winding 4G by current of reverse polarity, causing signal 4 to indicate caution and energizing relay 4PC, which causes signal 10 in the rear to indicate proceed. Relay 10PC picks up and releases relay 10S, so that signal 8 in the rear also indicates proceed. Transformers 9E and 1W, in the rear of the train, are now energized over front contacts of relays 9PC and 10PC and transformer 4W is energized over front contacts of relays 4PC and 3PC to extend the territory supplied with steady alternating current to include section 4T.

When the eastbound train occupies section 8T, signal 8 is similarly put to stop, relay 8S picks up and relay 8PC releases, signal 6 indicates caution, relay 6PC is energized and relay 6S releases, and signals 4 and 5 now indicate proceed. Relay 5PC becomes energized and energizes transformers 5E and 6W to supply steady alternating current to sections 5T and 6T behind the train. Finally, when the train vacates section 9T, the system for the single track stretch in the rear assumes its normal condition and steady alternating current is supplied to each of its sections.

Since the signal system is symmetrical for the two directions, the effect of a westbound train movement is similar to that described in respect to the control of the wayside and cab signals, but differs in that the motor car warning of an approach of a westbound train is provided by cutting off the supply of steady alternating current from the rails.

When the westbound train occupies section 9T, for example, the supply of current from transformers 8W and 7E in front of the train is cut off because relay 8PC releases instead of relay 1PC, from transformers 6W and 5E because relay 6PC releases, from transformer 4W because relay 4PC releases, and from transformers 1W and 9E beyond the siding in advance because relay 10PC releases.

In the motor car indication system just described, steady alternating current flowing in the track rails of a section indicates that no train is in the track section or approaching it from either direction within the control limits of the adja-

11

cent signals. Alternating current flowing in the track rails which is coded or interrupted at a relatively slow rate, such as 15 times per minute, indicates that an eastbound train is approaching the section within the control limits of the signals. The absence of alternating current in the track circuits or the presence of alternating current which is coded or interrupted at the rate of 180 times per minute indicates either that a westbound train is approaching, or that a train is in the same track section, or in some cases, in an immediately adjacent track section.

Fig. 2

Referring now to Fig. 2, a diagrammatic view of one arrangement of indication apparatus is there shown which may be employed on motor cars or other special vehicles which are operated over the stretch of track described above. As indicated diagrammatically in Fig. 2, the wheels W_1 and W_2 are insulated from the frame of the vehicle and from each other by interposing insulated bushings and washers 2 between the wheels and the axle AX . It is to be understood that the other pair of wheels, not shown, on the motor car are similarly insulated, so that the car will not shunt a track circuit. A slip ring SR_1 is electrically connected with the wheel W_1 and a second slip ring SR_2 is electrically connected with the wheel W_2 . Connected in series between the slip rings SR_1 and SR_2 are the condenser $1Q$ and the primary winding of a transformer ITT . The secondary winding of the transformer ITT is connected to the input terminals of a bridge-type rectifier IR_X , and the winding of an indicator relay IR is connected across the output terminals of this rectifier. It will be apparent that when the car moves over the rails of a track section the condenser $1Q$ will block the flow of direct current track circuit energy, but will permit the flow of alternating current from one track rail to the other through the primary winding of the transformer ITT . The alternating current induced in the secondary winding of transformer ITT is rectified by rectifier IR_X , and is supplied to the winding of relay IR , and as a result, relay IR picks up to establish a circuit, obvious from the drawing, for supplying energy over its front contact from the battery $1B$ to light the indicator lamp KE . If the supply of alternating current to the rails R is interrupted, current is no longer supplied to the winding of relay IR and its contacts release, extinguishing the lamp KE , and establishing a circuit for supplying energy to a warning bell KS . A switch SW is shown in series with the circuit for supplying energy to the indication lamp KE and the warning bell KS , so that the equipment may be deenergized when the car is removed from the rails.

It is to be understood that my invention is not limited to the specific arrangement of vehicle-carried indicator equipment shown in Fig. 2, and any suitable indicator means may be employed which will detect a distinctive indicating current supplied to the track rails and distinguish that current from the current used to energize the track relays. When alternating current is employed, as shown herein, the relay IR may be made responsive to current flowing in the track rails by the provision of receiving coils on the motor car in inductive relation to the rails, together with an amplifier for amplifying the energy induced in such coils, such an arrangement being well known from its use for the con-

12

trol of train-carried cab signals, as shown in the Lewis Patent No. 1,986,679 hereinbefore referred to.

It will be seen that if a car equipped with apparatus as shown in Fig. 2 travels over the stretch of track shown in Figs. 1A and 1B at a time when the system is in its normal condition with all of the track relays picked up, each of the track sections will in turn supply steady alternating current to the apparatus on the car and the relay IR on the car will remain energized, thus causing the lamp KE to remain lighted, and thereby indicate to the operator of the motor car that he may safely continue running.

It will be readily apparent, however, that the system of my invention differs very materially from the conventional cab signaling systems for the continuous control of train movements by apparatus responsive to alternating current in the track rails. In such systems, the track relay for the occupied section is shunted by the wheels and axles of the train, which complete a path for the cab signaling current from rail to rail in front of the train and this current is supplied to the rails at one end of the section or the other depending upon the traffic direction established. The motor car indication current on the other hand is supplied at one end only at each section for either direction of motor car operation, and its circuit is effectively completed from rail to rail in the manner indicated in Fig. 2 only in the absence of a train shunt. That is to say, the motor car current is supplied to the rails of a section over a circuit governed by the front contacts of the track relay for the section at a time when cab signaling current is not needed. It follows that a cab signaling system which embodies the approach control principle in which the control current is supplied to the rails of a section in response to the release of the track relay may be used in conjunction with my motor car indicator system without interference, merely by a choice of currents of different characteristics for the two systems.

Figs. 3A and 3B

In Figs. 3A and 3B a stretch of railway track is shown to which is applied a modified form of my supplemental signaling system for special vehicles. This stretch of track represents one track of a double-track railway, which is equipped with conventional wayside signals for single direction running only and also with cab signals for single direction running. The supplemental signaling system illustrated in these figures warns operators of motor cars of trains approaching from either direction, but does not inform the motor car operator as to the direction of approach.

The Figures 3A and 3B may be placed end to end either with Fig. 3B at the right of Fig. 3A or with Fig. 3B at the left of Fig. 3A.

The stretch of track shown in these figures is divided into sections 12T, 14T, 16T, and 18T, located immediately in advance of signals 12, 14, 16, and 18, respectively.

The motor car indication system of Figs. 3A and 3B not only governs the indicators carried on the cars, but also governs wayside indicators 12MC, 14MC, 16MC, and 18MC. These wayside indicators may be, for example, of the type shown and claimed in the copending application of Arthur W. Fisher and Wesley B. Wells, Serial No. 17,436, filed March 27, 1948, for Indicators.

The normal direction of traffic movement on

the stretch of railway track shown in Figs. 3A and 3B is eastbound, or from left to right in the drawings, as indicated by the arrows. The signals 12, 14, 16, and 18 control eastbound traffic only, no wayside signals being provided for westbound traffic.

The signals 12, 14, 16, and 18 are conventional color light signals having green, yellow and red lamps G, Y and R having lighting circuits which are governed in the manner shown for signal 12. When the track relay, such as relay 12TR for the section directly in advance of the signal, is released, its lamp R is lighted to indicate stop. When this track relay is energized, lamp Y is lighted to indicate caution provided an associated line relay 12DR is released, and lamp G is lighted in place of lamp Y to indicate proceed when the line relay is energized. Each line relay DR is controlled over a line circuit governed by the track relays for two sections in advance, as illustrated by the circuit for relay 12DR, which may be traced from positive battery terminal B at the location of signal 13 through the winding of a series approach relay 14XR, over front contact b of the track relay 14TR, line wire 17, front contact c of the track relay 12TR, the winding of relay 12DR, and thence over a common return line wire CL to the negative battery terminal C at the location of signal 14.

The XR relays have been included in the signal line circuits for the purposes of my improved motor car indication control system, and control a second series of line circuits.

Each line circuit of this second series includes at its left-hand end, a source of current, pole-changing contacts of a line relay YR and a front contact of the adjacent approach relay XR, and at its right-hand end includes the windings of an indication control relay ZR and of the pole-changer relay YR. Each relay ZR is of the biased polar type responsive to energy of one polarity only and picks up only when the controlling relays XR and YR are both energized. The relays YR are ordinary neutral relays and are repeaters of the controlling relays XR, and each is connected to its line circuit through a rectifier 20 to prevent its momentary release during a reversal of the polarity of the line current by the line relay YR which governs that circuit.

The line circuit of the second series extending between the locations of signals 12 and 14 may be traced from positive battery terminal B at the location of signal 12 over a front contact a of relay 12YR, line wire 19, front contact b of relay 14DR, front contact d of relay 14TR, through the winding of relay 14ZR, rectifier 20 and the winding of neutral relay 14YR, line wire 21, a front contact of relay 12XR, and front contact b of relay 12YR to negative battery terminal C at the location of signal 12. When relay 12YR is deenergized, the polarity of the energy supplied to the line circuit just traced is reversed, in which case relay 14YR remains picked up, since due to the rectifier 20 the direction of current through its winding remains unchanged, while relay 14ZR assumes its released position due to the fact that it is responsive to current of normal polarity only.

A branch circuit is provided for at times shunting the front contact b of relay 14DR and the front contact d of relay 14TR in the line circuit under discussion. This branch circuit may be traced from line wire 19 over a front contact a of a directional stick relay 14S to the right-hand terminal of the winding of relay 14ZR. 75

The contact b of relay 14DR and contact d of relay 14TR are provided in order to deenergize relay 14ZR whenever a train approaches from a direction opposite to the normal direction of traffic. The stick relay 14S and its contact a are provided to prevent such deenergization of relay 14ZR by an eastbound train moving in the normal direction and receding from the location of signal 14.

10 The circuits for the directional stick relays S are conventional. The pickup circuit for relay 14S may be traced from the positive battery terminal B at location 14 over back contact e of track relay 14TR, front contact c of relay 14DR, and thence through winding of relay 14S to negative battery terminal C. The stick circuit of relay 14S may be traced from the same positive battery terminal B through either back contact e of relay 14TR or back contact c of relay 14DR, and thence through front contact b of stick relay 14S, and the winding of relay 14S to negative battery terminal C. The pickup circuit for relay 14S is closed whenever a train moving from left to right passes signal 14. The stick circuit for relay 14S is then completed through its front contact b and remains completed until relay 14DR again picks up upon the departure of the train from sections 14T and 16T. The stick relay 14S therefore holds its contact a closed as long as contact c of relay 14DR is maintained open by deenergization of relay 14DR.

30 The wayside motor car indicator 14MC is energized over the line wires 19 and 21 through an obvious circuit which includes a front contact a of relay 14ZR.

35 The relay 14ZR also controls a contact b which selectively supplies the primary winding of a track transformer 12TT with steady alternating electrical current for motor car indication purposes when the relay 14ZR is energized or with coded alternating electrical current for cab signal purposes when the relay 14ZR is deenergized.

40 The circuit for supplying steady alternating current for motor car indication purposes to transformer 12TT may be traced from terminal BX of the local alternating current supply through front contact b of relay 14ZR, and primary winding of transformer 12TT to terminal CX of the alternating current supply.

45 The circuit for supplying coded cab signal current to transformer winding 12TT may be traced from another terminal BX of the alternating current supply over a contact of a code transmitter 18OCT, a front contact f of track relay 14TR, back contact b of relay 14ZR, and the primary winding of transformer 12TT to terminal CX of the alternating current supply.

50 The secondary winding of transformer 12TT is connected in series with the track battery 12TB and the usual current limiting impedance across the rails of section 12T at its exit end.

Operation of Figs. 3A and 3B

55 Let it be assumed that a train proceeding in the normal eastbound direction of traffic is proceeding through the track stretch with the signals ahead indicating proceed, and is just entering the track section 12T. The conventional wayside signal system operates in the usual manner, and a detailed discussion of it is believed to be unnecessary here. Briefly, occupancy of any track section by a train deenergizes its track relay and sets the signal at its entrance end to stop. Deenergization of the track relay also opens the line circuit to the DR relay for the next signal

15

in the rear, so that that signal is set to its caution position. The second and following signals in the rear of the occupied section will then indicate proceed.

When the train enters section 12T, relay 12TR releases to cause the display of a stop indication by signal 12, and opens its front contact *c* in the line circuit for relay 12DR which includes wires 17 and CL and the winding of relay 14XR at the next signal location in advance. Relay 14XR releases, opening its contact in the line circuit extending over line wires 22 and 23 to the location of signal 16, which is the second signal in advance of the occupied track section. Relays 16ZR and 16YR therefore release, but since relays 14TR and 16TR are picked up, relay 16XR is energized in series with relay 14DR over line wires 24 and CL and completes the line circuit which includes wires 25 and 26. Since relay 16YR is released, its pole-changing contacts *a* and *b* supply current of reverse polarity to this line circuit which extends to location of signal 18, the third signal in advance of the occupied track section. Current of reverse polarity flowing in this circuit causes the biased polar relay 18ZR to release, but maintains relay 18YR energized. Relay 18XR is energized in series with relay 16DR over line wires 27 and CL, allowing relay 18YR to supply current of normal polarity over line wires 28 and 29 to the location of the fourth signal in advance of the occupied section to energize relays corresponding to relays 12YR and 12ZR at that location, the relay corresponding to relay 12XR at the fourth location being energized in series with relay 18DR over line wire 30.

The release of relay 18ZR opens the energizing circuit for motor car indicator 18MC at its contact *a* and its contact *b* inserts a contact of a code transmitter 18OCT in the circuit for the primary winding of transformer 16TT, so that coded alternating current for cab signal control is supplied to the rails of section 16T in place of steady alternating current for motor car indication control.

Since at this time relay 16ZR is deenergized, as above described, its motor car wayside indicator 16MC is set to stop and its contact *b* operates to discontinue the supply of steady alternating current to transformer 14TT and substitutes the coded cab signal current.

The energizing circuit for relay 14ZR is opened at the front contact of relay 12XR, which relay was released by the track relay for the section in the rear of section 12T and is now held deenergized by the opening of front contact *b* of relay 12TR. Consequently, wayside motor car indicator 14MC is also set to stop, and the motor car indication current is removed from transformer 12TT and replaced by the coded cab signal current.

When the train above referred to entered section 12T, stick relay 12S picked up and its contact *a* bridges contact *b* of relay 12DR and contact *d* of relay 12TR in the energizing circuit for relays 12YR and 12ZR which includes line wires 28 and 29 and is held open by relay 18XR for section 18T in the rear of section 12T, relay 18XR being held released by the track relay 18TR until the train vacates that section. If there is no second train following the one in section 12T to maintain relay 18XR released, relays 12YR and 12ZR then become energized. Under this condition relay 12ZR will cause indicator 12MC to display a clear indication as soon as the train vacates the section in the rear, and will cause steady alternating current to be supplied through

16

transformer 18TT over front contact *b* of relay 12ZR to the rails of the section in the rear of the one occupied by the receding train.

When the train enters section 14T, relay 14TR releases and causes the indication of signal 14 to change from proceed to stop. The opening of contact *f* of relay 14TR cuts off the supply of coded current to the rails of section 12T, and relay 14S picks up over back contact *e* of relay 14TR. In addition, the opening of contact *c* of relay 14TR releases relays 14DR and 16XR, and relay 16XR deenergizes relays 18YR and 18ZR, the latter relay being already in its released position. Relay 18YR reverses the polarity of the current supplied over line wires 28 and 29 to the relays 12YR and 12ZR at the next location in advance, and this relay 12ZR releases to display a warning indication by the release of its indicator 12MC and to supply coded cab signal current in place of steady current to the rails of its section.

When the train vacates the rear section 12T, its track relay 12TR picks up to cause the indication of its signal 12 to change from stop to caution. Relays 12DR and 14XR are held released by the opening of contact *b* of relay 14TR, and relay 12S is held energized over back contact *c* of relay 12DR. If there is no following train within its control limits, relay 12XR picks up over contact *b* of relay 12TR, and if relay 12YR is also energized, relays 14YR and 14ZR pick up over contact *a* of relay 14S. Relay 14ZR then energizes indicator 14MC and supplies steady alternating current to the rails of section 12T.

When the train advances into section 16T, the indication of signal 16 changes from proceed to stop, the supply of coded current to section 14T is cut off, relay 16S picks up, and relays 16DR and 18XR release, due to the release of relay 16TR. In front of the train, relay 18XR deenergizes relays 12YR and 12ZR at the next location in advance and relay 12YR releases relay 14ZR to extend the motor car warning limit to include the second location in advance.

When the train in section 16T vacates the rear section 14T, its track relay 14TR picks up to cause the indication of signal 14 to change from stop to caution, and to reenergize relays 12DR and 14XR. Relay 12DR causes the indication of the rear signal 12 to change from caution to proceed, and releases relay 12S. If there is no train following the one in section 16T, relays 12YR and 12ZR in the rear are maintained energized over contact *d* of relay 12TR and contact *b* of relay 12TR, and relays 14YR and 14ZR are energized over contact *a* of relay 14S. Relays 14XR and 16ZR pick up, due to the energization of relay 14XR, and relay 16ZR energizes indicator 16MC and supplies steady alternating current to the rails of section 14T.

From the foregoing, it may be seen that an eastbound train occupying a track section deenergizes the wayside motor car indicators at the three signal locations in advance of the occupied section, and causes the supply of steady alternating electrical current, the presence of which indicates to a motor car operator that no train is approaching, to be cut off from the rails of the section occupied by the train and from the rails of the two sections in advance, and also causes coded alternating current for cab signal purposes to be supplied to the rails of these sections.

Consider now the conditions which occur when a train is moving westbound, opposite to the nor-

mal direction of traffic through the stretch of track shown in the drawings. Let it be assumed that a westbound train is entering section 16T. The shunting effect of its wheels and axles prevents transformer 16TT from supplying current to the rails of that portion of section 16T which is in front of the train, and also deenergizes track relay 16TR, which opens its contact *d* in the circuit of relay 16ZR. Deenergization of relay 16ZR sets the wayside motor car indicator 16MC to stop, and interrupts the supply of steady alternating current to transformer 14TT. The supply of coded cab signal current to transformer 14TT is interrupted at front contact *f* of relay 16TR.

At the same time, opening of contact *b* of relay 16TR opens the circuit of relay 14DR. Relay 14DR releases and its contact *b* opens the energizing circuit of relay 14ZR. Wayside motor car indicator 14MC is therefore also set to stop and the supply of current to track transformer 12TT is changed from steady to coded alternating current.

It may therefore be seen that a westbound train deenergizes the wayside motor car indicators at two locations in advance and removes the motor car indication current from two track sections in advance.

It will also be seen that for either direction of train movement, when a train enters a block section the zone of motor car protection is extended to include three full sections in advance of the train, this zone decreasing to two sections as the train approaches the exit end of the section through which it is moving.

Although I have shown in this system the use of both wayside motor car indicators, such as those indicated at MC in the drawings, and car-carried indicators such as illustrated in Fig. 2, it should be understood that either one of these may be used to the exclusion of the other, if desired.

The cab signal system illustrated herein gives to the engineman an indication of the condition of the next track section in advance, as to whether or not it is occupied. For example, the supply of cab signal energy to transformer 12TT is controlled by front contact *f* of relay 14TR. Accordingly, the cab signal energy is supplied to the rails of section 12T only if section 14T is unoccupied. The back contacts *b* of the ZR relays in this system provide approach control for the cab signals, and it will be seen that the cab signal current is supplied to the rails of a given section only when a train is within or approaching that section.

Although I have herein shown and described only two signaling systems embodying my invention, it is understood that various changes and modifications may be made therein within the scope of the appended claims without departing from the spirit and scope of my invention.

Having thus described my invention, what I claim is:

1. In combination with a stretch of railway track divided into a plurality of sections each having a track relay which is normally energized by current supplied to the rails of its section and which releases due to the shunting effect of the wheels and axles when a train occupies its section, said stretch being provided with a railway signaling system controlled by said track relays for governing the movement of trains through said stretch, a supplementary signaling system for the protection of special vehicles in said stretch which are not adapted to shunt said track relays, com-

prising indication means on each special vehicle selectively responsive to indication current in the track rails of one character or another different from that normally supplied to said track relays, and indication current supply means controlled by said track relays and effective to supply indication current of said one character to the rails of each section only when that section is unoccupied, said means being further effective to cut off said indication current when a train approaches the section from one direction and to supply indication current of the other character when and only when a train approaches the section from the opposite direction.

15 2. In combination with a stretch of railway track arranged for the operation of trains each equipped with train-carried signaling apparatus including a receiver responsive to certain periodically interrupted alternating currents flowing in the track rails, said stretch of track being divided into sections each having a track relay which is normally energized by direct current supplied through the rails of its section and which releases due to the shunting effect of the wheels and axles when a train occupies its section, a signaling system for the protection of special vehicles in said stretch which are not adapted to shunt said track relays, comprising indication means on said special vehicles responsive to alternating current in the track rails, indication controlling means for each section controlled by the track relays of a plurality of said sections, a first source of periodically interrupted alternating current of a type to which said train-carried receivers are responsive, a second source of periodically interrupted alternating current of a distinctively different type to which said special vehicle receivers are responsive, a source of steady alternating current, and contacts operated by each said indication controlling means effective to connect said first source to the track rails of its section whenever such section is occupied by a train, to connect said second source to the rails of such section only when a train is approaching said section within a predetermined distance in one direction, to disconnect all said sources from the rails of such section when a train is approaching within a predetermined distance in the opposite direction, and to connect said source of steady alternating current to the rails of such section only when said section is unoccupied by a train and no train is approaching within a predetermined distance in either direction.

3. In combination with a stretch of railway track divided into a plurality of sections each having a track relay which is normally energized by direct current supplied to the rails of its section and which releases due to the shunting effect of the wheels and axles when a train occupies its section, said stretch being provided with a railway signaling system controlled by said track relays for governing the movement of trains through said stretch, said signaling system including two sets of signals for controlling traffic in opposite directions and corresponding sets of contacts movable substantially concurrently with operation of said signals to open and close circuits corresponding to the signal indications; a supplementary signaling system for the protection of special vehicles in said stretch which are not adapted to shunt said track relays, comprising indication means on each special vehicle responsive to alternating current in the track rails; a source of steady alternating current, a source of coded alternating current, first circuit means for each

section controlled by a contact of one of said sets of contacts for disconnecting both of said sources from the rails of said section when a train is approaching from one direction and for permitting connection of said sources to the rails at other times; and second circuit means for each section controlled by a contact of the other set of contacts and effective when said first circuit means permits connection of the sources to the rails to connect said first source to the rails when no train is approaching and to connect said second source to the rails when a train is approaching from the opposite direction.

4. In combination with a stretch of railway track arranged for the operation of trains each equipped with train-carried signaling apparatus including a receiver responsive to coded alternating currents flowing in the track rails, said stretch of track being divided into a plurality of sections each having a track relay which is normally energized by direct current supplied to the rails of its section and which releases due to the shunting effect of the wheels and axles when a train occupies its section, said stretch being provided with a wayside block signaling system controlled by said track relays for governing the movement of trains through said stretch, said signaling system including two sets of signals for controlling traffic in opposite directions and corresponding sets of electric contacts movable substantially concurrently with said signals to open and close circuits corresponding to the signal indications; a supplementary signaling system for the protection of special vehicles in said stretch which are not adapted to shunt said track relay, comprising indication means on each special vehicle responsive to alternating current in the track rails; a first source of current adapted to supply steady alternating current to the rails of the section, a second source of current adapted to supply coded alternating current to the rails of the section to which said train-carried apparatus is nonresponsive, a third source of current adapted to supply differently coded alternating current to said rails of a type to which said train-carried apparatus is selectively responsive, a first circuit means for each section including the track relay thereof and effective when the section is occupied to connect only said third source to the rails, and means controlled jointly by the sets of contacts associated with signals for governing traffic in opposite directions and effective only when said track relay is energized to connect said first source to the rails of the section when no train is approaching within a predetermined distance in either direction, to connect said second source to the rails when a train is approaching within said distance in one direction, and to disconnect both said first and second source from the rails when a train is approaching within said distance in the opposite direction.

5. In combination with a stretch of railway track divided into a plurality of sections each having a track relay which is normally energized by direct current supplied to the rails of its section and which releases due to the shunting effect of the wheels and axles when a train occupies its section, said stretch being provided with a railway signaling system controlled by said track relays for governing the movement of trains through said stretch, said signaling system including two sets of signals for controlling traffic in opposite directions and corresponding sets of contacts movable substantially con-

currently with operation of said signals to open and close electric circuits corresponding to the signal indications; a supplementary signaling system for the protection of special vehicles in said stretch which are not adapted to shunt said track relays, comprising indication means on each special vehicle responsive to alternating current in the track rails; a source of steady alternating current, a source of coded alternating current, means for each section controlled jointly by the sets of contacts for the signals controlling traffic in opposite directions for connecting said first source to the rails of said section when no train is approaching said section within a predetermined distance, for disconnecting both of said sources from the rails when a train approaches within said distance in one direction, and for disconnecting said first source and connecting said second source to the rails when a train is approaching said section and is within a predetermined distance in the opposite direction, and directionally controlled means for connecting said first source to the rails behind a receding train until said contacts are again operated in response to train movements in said stretch to provide a different connection.

6. In combination with a stretch of railway track divided into a plurality of sections each having a track relay which is normally energized by current supplied to the rails of its section and which releases due to the shunting effect of the wheels and axles when a train occupies its section, said stretch being provided with a railway signaling system controlled by said track relays for governing the movement of trains through said stretch, a supplementary signaling system for the protection of special vehicles in said stretch which are not adapted to shunt said track relays, comprising indication means on each special vehicle selectively responsive to indication current in the track rails of one character or another different from that normally supplied to said track relays, and indication current supply means controlled by said track relays and effective to supply indication current of said one character to the rails of each section only when that section is unoccupied, said means being further effective to cut off said indication current in each section occupied by a train and in at least one section immediately in advance of any section occupied by a train moving in one direction and to supply indication current of the other character to at least one section immediately in advance of any section occupied by a train moving in the opposite direction.

7. In combination with a stretch of railway track divided into a plurality of sections each having a track relay which is normally energized by current supplied to the rails of its section and which releases due to the shunting effect of the wheels and axles when a train occupies its section, said stretch being provided with a railway signaling system controlled by said track relays for governing the movement of trains through said stretch, a supplementary signaling system for the protection of special vehicles in said stretch which are not adapted to shunt said track relays, comprising indication means on each special vehicle selectively responsive to indication current in the track rails of one character or another different from that normally supplied to said track relays, and indication current supply means controlled by said track relays and effective to supply indication current of said one character to the rails of each section only when that

section is unoccupied, said means being further effective to cut off said indication current from the rails of each section occupied by a train and from the rails of a plurality of sections in advance of a train moving in one direction and to supply indication current of the other character to the rails of a plurality of sections in advance of a train moving in the opposite direction.
